Attorney

UNITED STATES PATENT OFFICE.

JOHN L. FITZPATRICK, OF BOWLING GREEN, KENTUCKY.

VALVE CONSTRUCTION.

Application filed November 25, 1927. Serial No. 235,588.

My invention relates to improvements in valve constructions, and relates particularly to means for securing valve members in association with inflatable bodies, such as the bladders of footballs, basket balls, and the like.

The nature of my device resides in providing a valve construction, the outer portion of which will be substantially disposed in flush relation with the exterior of the inflatable body, when the same has been inflated.

The main object of this valve structure, residing in providing means whereby the same may be removed when it becomes necessary to replace the same because of defects, or where the bladder has become ruptured as is desired to save the valve.

Another object resides in providing such a valve structure, which may be quickly and efficiently clamped in position with respect to inflated bladder.

Other very novel objects and advantages will become apparent as the same is better understood from the specification and claim to follow.

In the drawing:—

Figure 1 discloses a fragmentary view of a conventional bladder, showing my improved valve construction in sectional detail view, and

Fig. 2 discloses a top plan view of the improved valve structure.

Now for a more detail description of my invention, I refer to the drawings, in which like numerals designate like parts. In the drawing for the purpose of illustrating the manner in which my improved valve construction is associated with inflatable bodies, I designate a conventional bladder A, of a football, basketball, or the like. The bladder is formed with the usual valve receiving opening, through which my valve is adapted to be inserted and secured.

The construction of this valve includes a cup-shaped valve carrying member 1, which is provided at its open end with a lateral circumferentially extending flange 2. Between the flange 2 and the cup 1, the material is thickened at 3, for the obvious purpose of strengthening the same.

As is shown in the drawing, the diameter of this cap is substantially the same as the diameter of the opening formed in the inflatable body A. A tapering tubular member 4 is adapted for disposition within the cap and is preferably polygonal in cross section, whereby an insertable wrench may engage within the same, for removing the same from its complementary relation with the cup 1. The inner end of the tubular member is provided with a relatively thick wall 5, having a threaded bore substantially through the center thereof. The outer open end of the tube is formed with the laterally disposed circumferential flange 6, its under side adapted to engage the portion of the inflatable member adjacent the opening therein, while its top surface is converged toward the bladder.

As is clearly shown in Fig. 1 of the drawing, a valve body B of conventional type, especially the type having its longitudinal extent threaded in a manner as shown. The inner end of this valve body is adapted to be secured by welding, soldering, or any other well known process, within an opening in the inner wall of the cup 1. This valve body is adapted to project upwardly through the cup and to terminate substantially flush with its top edge.

When the bladder is in deflated condition, the cup 1 may easily be inserted through the opening therein and positioned in the manner shown in Fig. 1. In this position, the flange 2 thereof is disposed against the inner side portion adjacent the opening, while the tapering tubular member 4 is threaded through the opening, and threaded upon the threaded valve body B. A rubber washer 7 is disposed between the bladder and the under side of the flange 6, so that when the member 4 is fed inwardly to the point where the flange 6 is engaging the washer 7 tightly against the bladder, the flange 2 is in a clamping position against the inner side of the bladder.

In this manner, it will be seen that this structure provides a novel and efficient valve construction, wherein the liability of leak is reduced. It will also be seen that I have provided a valve device, which while perhaps costing slightly more in cost to manufacture,

the same may be retained after a bladder has been ruptured, and is employed in conjunction with a new bladder.

Having thus described my invention, what I claim as new is:—

5 In a valve securing means for inflatable bladders wherein it employs a conventional threaded valve body, a cup having a flange at its open end adapted to bear against the inner side of the plate about the usual valve receiv-

ing opening therein, said cup adapted to have the conventional threaded valve body extending therethru, a tube having a flange at its outer end engageable with the outer side of the bladder, the inner end of the tube being in 15 threaded relation with the threaded valve body, whereby the flanges may be clamped to opposite sides of the bladder.

In testimony whereof I affix my signature.

JOHN L. FITZPATRICK.
